(57) **CLAIM**

The ornamental design for a baseball, as shown and described.

DESCRIPTION

FIG. 1 is a top perspective view of a baseball showing my new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in FIGS. 1 and 2 are included for the purpose of illustrating inner portions of the baseball that form no part of the claimed design.
